9 Claims

ABSTRACT OF THE DISCLOSURE

A detergent composition is disclosed containing about 40 to 90% of an alkaline builder, a minor amount of an ammonium salt of a styrene maleic anhydride resin of about 1 to 4 moles of styrene per mole of maleic anhydride, and about 10 to 50% of a non-ionic, hydroxyl-containing surfactant condensation product of an alkylene oxide of about 2 to 6 carbon atoms. Additionally the styrenemaleic anhydride resin may be partially esterified with the non-ionic surfactant.

This invention relates to improved detergent compositions for the laundering of textiles. More particularly, it concerns the use of styrene-maleic anhydride resins in laundry detergents to form compositions which possess excellent emulsifying, dispersing and suspending properties and, therefore, show exceptional cleaning power.

A large number of detergent compositions are known in the art and they generally include the many well-known detergents used in the household, as well as the heavy duty detergents which are used in industrial operations for cleaning highly soiled textiles. New synthetic fabrics, for example, Dacron and Dacron-cotton containing materials, present many cleaning problems for present day detergents. One of the difficulties encountered in laundering synthetic fabrics using these detergents concerns the ability to remove heavy soils and at the same time retain fabric whiteness. These detergent compositions must generally use laundering temperatures of about 190-195° F. for industrial laundering and about 120-150° F. for household laundering to obtain satisfactory soil removal. Although these temperatures afford satisfactory cleaning, it has been found that during the first several washings, the colored fabrics may bleed excessively and the color may be picked up by the lighter colored fabrics in the wash. Conventional detergents also suffer from many other deficiencies such as poor emulsifying and inadequate dispersing properties; and after the removal of the soil from the fabric, an inadequacy towards preventing the redeposition of the soil and dye on the fabric before the laundering cycle is completed.

According to the present invention, improved detergent compositions have been produced which are very effective for cleaning highly soiled textiles such as synthetic fabrics, for example, Dacron and Dacron-cotton containing fabrics, and at the same time will retain fabric whiteness. These improved detergents prevent deposition of soil and dye on the textile by their suspending action, and therefore will provide greatly improved whiteness retention during laundering. The laundry detergents of the present invention also possess effective emulsifying, wetting and dispersing properties, excellent stability, and outstanding cleaning power for removing oil, grease, carbon black and other types of dirt from textiles.

In accordance with the present invention, it has been discovered that detergent compositions containing styrene-

2

maleic anhydride resins in combination with hydroxyl-containing nonionic surfactants afford the improvements and advantages discussed above. In the detergent compositions of the present invention, the styrene-maleic anhydride resins have several functions. Because of their surface-active properties, these resins can act as stabilizers for liquid detergents, preventing their breakdown into a two-phase system. They also may act as part of the organic active component aiding in the wetting of the fabric and soil, and further as dispersing agents by dispersing the dirt out of the fabric into the washing medium. Most important, the styrene-maleic anhydride resins can function as suspending agents by suspending dirt and dye in the washing medium, thus preventing redeposition of the dirt or dye on the fabric. The styrene-maleic anhydride resin component of these detergents may be utilized either as such or as a partial ester thereof or, more advantageously, as a partial ester with a hydroxyl-containing nonionic surfactant, such as, for example, the reaction products of alkyl phenols with alkylene oxides.

The styrene-maleic anhydride resins used in the detergent composition of the present invention are the ammonium salts of these resins, including their partial ester derivatives, having about 1 to 4 moles, preferably about 1 to 3 moles of styrene per mole of maleic anhydride. If desired, maleic acid can be used instead of maleic anhydride in formation of the resins with styrene. These resinous polymers contain repeating styrene-maleic anhydride units and preferably have an average molecular weight of at least about 500 to about 50,000. The preferred average molecular weight of the resins is about 700 to 3000. The melting points of these lower molecular weight polymers will often range from about 100 to 200° C. as determined by the Fisher-Johns melting point apparatus. The determination of average molecular weight as used herein is made by the thermoelectric differential vapor pressure lowering method on a microlab osmometer. The polymers of styrene and maleic anhydride can be prepared by known methods. A preferred method is by solution polymerization where the monomers are polymerized in a suitable solvent employing as a polymerization catalyst a free-radical peroxide catalyst, preferably benzoyl peroxide or dicumyl peroxide, at a temperature of about 75 to 300° C. or more. Suitable solvents include the aromatic hydrocarbon solvents, such as cumene, p-cymene, xylene, toluene, etc. The aromatic solvents may serve as chain-terminating solvents and give lower molecular weight products. Other suitable solvents are the ketones, such as methyl ethyl ketone, which may also be chain-terminating solvents. The preferred manner of carrying out the polymerization is by what is known in the art as incremental feed addition. By this method the monomers and catalyst are first dissolved in a portion of the solvent in which the polymerization is to be conducted and the resulting solution fed in increments into a reactor containing solvent heated to reaction temperature, usually the reflux temperature of the mixture. When an aromatic solvent is employed as the solvent for the polymerization, the formation of the polymers causes a heterogeneous system, the polymer layer being the heavier layer and recoverable by merely decanting the upper aromatic solvent layer and drying. On the other hand, when a ketone is the solvent, the formed polymer is usually soluble in the solvent media so that recovery of the products necessitates a solvent-stripping operation. The styrene-maleic anhydride resins can be used in minor amounts, e.g., of about 0.1-20 percent by weight of the total solids of the detergent composition, preferably about 1-10 percent. By total solids of the detergent composition is meant the components other than water and hydrocarbon solvent, if any be present.

The hydroxyl-containing nonionic surfactants or organic active components of the present invention are the condensation products of an alkylene oxide of say 2 to 6 carbon atoms such as, for example, ethylene oxide, propylene oxide, butylene oxide, hexylene oxide, etc., preferably ethylene oxide, with an organic compound containing at least 6 carbon atoms and often up to about 30 carbon atoms or more, and a reactive hydrogen atom. Such compounds containing reactive hydrogen atoms include aromatic, mono- and poly-hydroxy compounds such as phenols, naphthols, benzene and naphthalene diols, triols, tetrols, and the like. In this group, alkyl phenols containing from 1 to 3 alkyl substituents of from 4 to 20 carbon atoms each are preferred. Some examples of such compounds are the normal and isomeric mono-, di- and tri-butyl, nonyl, and octadecyl-phenols and cresols; and phenols and cresols which may be substituted with a plurality of different such alkyl groups. Another preferred group of compounds containing reactive hydrogen groups include aliphatic mono- and poly-hydroxy compounds such as fatty alcohols. Such compounds often have up to about 25 carbon atoms, e.g. trimethylene glycol, glycerol, allyl alcohol, sec-butyl alcohol, butanediol 1,3, isopropylvinyl carbinol, octanediol 1,2, lauryl alcohol, pentadecanol, cetyl alcohol, octadecanol, docosanol, pentaeicosanol, etc.

The amount of alkylene oxide condensed with the reactive hydrogen-containing compounds, i.e., the length of the oxyalkylene chain, may depend upon the particular compound with which it is condensed and also the particular styrene-maleic anhydride resin used. Generally, an amount of alkylene oxide should be employed which will result in a condensation product containing from about 20 to 85 percent by weight of combined alkylene oxide. However, the effective amount of alkylene oxide for obtaining the desired balance, may be readily determined in any particular case by preliminary tests and routine experimentation. For example, the number of ethylene oxide units may often be from about 4 to 15 depending upon the particular styrene-maleic anhydride resin used. The nonionic surfactants can be present in the detergent composition in amounts, e.g. of about 10 to 50% by weight, advantageously about 20 to 50%, based on the solids of this composition.

When the nonionic surfactants and the styrene-maleic anhydride resins are combined in the detergent composition, they may be present as a physical mixture or as a partial ester of the nonionic hydroxyl-containing surfactant with styrene-maleic anhydride resin. The partial esters can be readily prepared by bulk reaction of molten styrene-maleic anhydride resins with the hydroxyl-containing surfactants or may be prepared by reaction in solution. Physical mixtures are prepared by solution of the nonionic surfactants and styrene-maleic anhydride resins in dilute aqueous alkali. Such mixtures may have present some partial esters of the surfactant and resin.

Although styrene-maleic anhydride resins will combine with the nonionic surfactants mentioned above to achieve the combination necessary to produce the improved detergents of the present invention, it has been found that a detergent with particular effectiveness can be obtained by balancing the hydrophobic-hydrophylic characteristics of the styrene-maleic anhydride resin and the nonionic surfactants with the wash temperatures. For example, the styrene-maleic anhydride resins afford maximum effective properties to the detergent composition when combined with nonionic surfactants containing about 4 to 12 ethylene oxide units, often about 9 to 12 ethylene oxide units when using a wash temperature of about 120-170° F. When the desired wash temperature is about 170-190° F., maximum properties are obtained when the styrene-maleic anhydride resins are combined with nonionic surfactants containing about 12-15 ethylene oxide units.

A typical heavy duty detergent composition incorporating the styrene-maleic anhydride resins and the nonionic surfactants of the present invention is shown in Table I.

TABLE I

5	Component:	Parts by wt.
	Tergitol 15-S-12 ¹ (nonionic surface active agent)	60.0
10	Styrene-maleic anhydride resin A ²	5.0
	Sodium silicate	58.0
	Sodium hydroxide	12.0
	Potassium pyrophosphate	30.0
	CMC-T ³ (suspending aid) (optional)	1.0

¹ Condensation product of a secondary alcohol of about 15 carbon atoms with ethylene oxide in a mole ratio of about 1:12.

² Ammonium salt of a styrene-maleic anhydride resin, having a styrene to maleic anhydride ratio of 2:1, mol. wt. ~1700.

³ Sodium carboxymethylcellulose, technical grade.

20 As can be observed from Table I, the detergent compositions of the present invention may also include other conventional detergent constituents such as, for example, alkaline builders and may, if desired, include fabric whiteners, other soil suspending agents, etc. Alkaline builders function as water softeners and also aid in the removal and suspension of dirt and often represent about 40 to 90 percent of the detergent compositions based on total solids, preferably about 50 to 70%. Typical alkaline builders which can be used in heavy duty detergent compositions include alkali metal carbonates, borates, phosphates, bicarbonates, silicates, sulfates, ammonia, organic amides, and the like. Although the styrene maleic anhydride resins function as soil suspending agents, additional suspending aids may be used. These soil suspending aids act with the styrene maleic anhydride resins in the detergent composition to suspend the soil in the washing medium and prevent redeposition of the soil on the fabric. The soil suspending agents which can be used in detergent compositions are generally water-soluble polymeric materials such as cellulose glycolic acid, cellulose ethane sulfonic acid, hydroxy-ethyl methyl cellulose, starch, hydroxyethyl starch, starch glycolic acid, poly-alkylene glycols, etc. The soil suspending aids when used in the detergent composition of the present invention may be present in amounts up to about 1% or more by weight of the total solids. The fabric whiteners which may be used are dependent primarily on the particular fabric to be cleaned, and any type normally utilized in such detergents for whitening and brightening effects may be employed. As examples of such agents there may be mentioned stilbenes, diamino stilbenes, acylated, cyanuric and triazolyl derivatives of such stilbenes, diphenyl derivatives, dibenzothiophene derivatives, aminocoumarone salts, derivatives of diazotized amino-containing benzoxazole, benzthiazole and benzimidazole compounds, and the like. The fabric whiteners when used in the aqueous detergent composition of the present invention may be present in amounts of 0.05 to about 0.25% by weight. It may also be desired to include a hydrocarbon solvent in the detergent composition of the present invention. In such a case the solvent may be present for example in amounts of 0.5 to about 2% of the aqueous composition.

65 The total amount of detergent of the present invention which can be used in a wash solution can vary depending for example upon the textiles to be washed, the amount of soil contained in the textiles, laundering temperature, etc. However, a total detergent amount of 0.05 to about 2% by weight has been found to be effective for washing solutions.

70 The advantages of using the maleic anhydride resins and the nonionic surfactants in heavy duty detergent composition over detergents not containing these additives will be apparent by referring to the following examples.

EXAMPLE I

A series of different detergent compositions was prepared using nonionic surfactants, styrene-maleic anhy-

tion were measured. Table II gives the concentrations of the various components as they were present in the wash solution and the results of these tests.

dride resins and inorganic builders. No suspending aids or whitening agents were used so as not to confuse the exceptional properties imparted by the styrene-maleic anhydride resins. White Dacron-cotton fabrics containing 65% Dacron and 35% cotton were partially soiled with No. 6 fuel oil so that each fabric consisted of a soiled and an unsoiled portion. The soiled cloths were allowed to age for about 18 hours. The fabrics were then washed for about 15 minutes in pint jars in a Launderometer with mild agitation and rinsed. Both soil removal and soil redeposi-

EXAMPLE II

The detergent compositions of Example I were treated with Tintex 25 Navy Blue dye so that the dye was present in an amount of 0.025% in the washing media. White Dacron-cotton fabrics containing 65% Dacron and 35% cotton were washed for 15 minutes in these dilute dye solutions and the deposition of dye on the fabric measured. The fabrics were not rinsed. These experiments gave more controllable dye concentrations than does the actual fading of colored fabrics. Results of these tests are given in Table III.

¹ Ammonium salt of Resin B—Tergitol 15-S-12 partial ester. About 5% half ester of styrene-maleic anhydride resin B with Tergitol 15-S-12 (identified earlier) and 65% half ester with n-propyl alcohol.

² Resin C—Ammonium salt of 50% half-ester of styrene-maleic anhydride resin D with butylcellosolve.

Resin D—1:1 styrene to maleic anhydride mole ratio, mol. wt.=1600.

EXAMPLE V

The experiments in Example IV were repeated using four 2 x 3' pieces of navy blue Dacron-cotton fabric containing 65% Dacron and 35% cotton per 1000 ml. wash solution instead of the Tintex dye. The navy blue

material faded during the wash cycle and the capacity of the detergent compositions to prevent dye deposition on the white Dacron-cotton fabric was measured. The results were the same as in Example IV presented in Table V.

To illustrate the advantages of using the ammonium

salt of the styrene-maleic anhydride resins in the detergent compositions of the present invention rather than the alkali metal salts of these resins a series of experiments were conducted comparing their dye and soil suspending properties. The results are summarized in Table VI.

¹ Get same results with styrene maleic anhydride potassium salt as with sodium salt.

² Condensation product of fatty alcohol of about 12-18 carbon atoms with ethylene oxide in a mole ratio of about 1:12.

*Equal cleaning in all cases.

As can be seen in Table VI, experiments 1 to 4 show the ammonium salt of the styrene-maleic anhydride resins to be superior to the sodium salt of these resins as a dye suspending agent. Experiments 5 to 8 also show the ammonium salt of these resins to be superior to the sodium form as a soil suspending agent.

Experiments 9 to 11 in Table VII show that it is advantageous to use the higher ratios of styrene to maleic anhydride in the detergent compositions of the present invention.

TABLE VII.—MEASUREMENT OF SOIL SUSPENSION

[1:1, 2:1, 3:1 styrene:maleic anhydride]

All concentrations same as previous soil suspending case (experiments 5-8) except for suspending agent.

Detergent concentration in wash solution:

Surfonic LR-120	0.3%
Potassium pyrophosphate	0.5%
Potassium carbonate	0.25%
Hydrocarbon solvent	1.0%

Experiment	Suspending Agent	Suspending Agent Amount (Percent)	Results ¹
9	Styrene-maleic anhydride (1:1) polymer, mol. wt. ~1600.	0.00	Very poor soil suspension.
10	Styrene-maleic anhydride (2:1 polymer, mol. wt. ~1700).	0.05	Good soil suspension. Slight deposition on fabric.
11	Styrene-maleic anhydride (3:1 polymer, mol. wt. ~1600).	0.05	Excellent soil suspension. No deposition on white portion of fabric.

¹ The cleaning power was equivalent in all examples.

It is claimed:

1. A laundry detergent composition consisting essentially of about 40 to 90 weight percent of alkaline builder, about 0.1 to 20 weight percent of the ammonium salt of resinous polymer consisting essentially of styrene and maleic anhydride having a mole ratio of about 1 to 4 moles of styrene per mole of maleic anhydride and a molecular weight of about 500 to 50,000, and about 10 to 50 weight percent non-ionic, hydroxyl-containing surfactant condensation product of alkylene oxide of about 2 to 6 carbon atoms and hydroxyl-containing organic compound containing about 6 to 30 carbon atoms, said amounts being based on total solids, said condensation product having about 20 to 85 weight percent of said alkylene oxide.

2. The composition of claim 10 wherein said styrene-maleic anhydride polymer and said condensation product are present in the detergent composition as a physical mixture.

3. The composition of claim 10 wherein the styrene-maleic anhydride polymer is present in the detergent composition as a partial ester of said polymer with said non-ionic, hydroxyl-containing surfactant.

4. The composition of claim 10 wherein said alkylene oxide is ethylene oxide and the styrene-maleic anhydride polymer has a molecular weight of about 700 to 3000.

5. The composition of claim 13 wherein said alkaline builder is present in an amount of about 50 to 70 weight percent, the ammonium salt of the styrene-maleic anhydride polymer is present in an amount of about 1 to 10 weight percent, and the non-ionic hydroxyl-containing surfactant is present in an amount of about 20 to 50 weight percent.

10 6. The composition of claim 10 wherein the non-ionic hydroxyl-containing surfactant has about 4 to 15 ethylene oxide units.

7. A laundry detergent composition consisting essentially of about 40 to 90 weight percent of alkaline builder, about 0.1 to 20 weight percent of the ammonium salt of a resinous polymer consisting essentially of styrene and maleic anhydride having a mole ratio of about 1 to 3 moles of styrene per mole of maleic anhydride and a molecular weight of about 700 to 3000, and about 10 to 50% of non-ionic, hydroxyl-containing surfactant consisting essentially of the condensation product of ethylene oxide and a compound selected from the group consisting of alkyl phenols of from about 1 to 3 alkyl substituents of from about 4 to 20 carbon atoms each, and fatty alcohols of up to about 25 carbon atoms, said condensation product having about 9 to 15 ethylene oxide units, said amounts being based on total solids of the composition.

8. The composition of claim 5 wherein the alkaline builder is present in an amount of about 50 to 70 weight percent, the ammonium salt of the styrene-maleic anhydride polymer is present in an amount of about 1 to 10 weight percent, and the non-ionic, hydroxyl-containing surfactant is present in an amount of about 20 to 50 weight percent.

35 9. The composition of claim 7 wherein the condensation product is of ethylene oxide and nonyl phenol.

UNITED STATES PATENT OFFICE
CERTIFICATE OF CORRECTION

Patent No. 3,485,762 Dated December 23, 1969

Inventor(s) Robert G. Gower, Henry V. Isaacson & David W. Young

It is certified that error appears in the above-identified patent and that said Letters Patent are hereby corrected as shown below:

In Table VI, between the column headed "Hydrocarbon Solvent" and the column headed "Dye Amount", insert an additional column headed --Dye--.

In Table VI, in said additional column headed "Dye", and opposite each of Experiments 1, 2, 3, and 4, insert --Tintex 25 Navy Blue--.

In Table VI, above "No. 6 fuel oil" in Experiment 5, insert a column heading entitled --Soil--.

In Table VII, Experiment 9, delete "0.00" and insert therefor --0.05--.

In claims 2,3,4 and 6, line 1 of each, delete "10" and insert therefor --1--.

In claim 5, line 1 thereof, delete "13" and insert therefor --4--.

In claim 8, line 1 thereof, delete "5" and insert therefor --7--.

Signed and sealed this 30th day of March 1971.
